INSULATED MOUNTING

Michael J. Zunick, Greenfield, Wis., assignor to General Electric Company, a corporation of New York

Original application March 13, 1952, Serial No. 276,313, now Patent No. 2,732,510, dated January 24, 1956. 10 Divided and this application June 17, 1953, Serial No. 362,207

3 Claims. (Cl. 174—152)

The present invention relates in general to electronics, and has more particular reference to electron emitters, the invention pertaining especially to an improved support structure for filaments of the sort commonly employed as electron emitting cathodes in electron flow devices, such as X-ray generating tubes and the like. The invention comprises subject matter divided from a pending application for United States Letters Patent, Serial No. 276,313, filed March 13, 1952, in response to which U. S. Patent No. 2,732,510 was issued on January 24, 1956.

X-ray generating tubes commonly comprise an anode and an electron emitting cathode element enclosed in a sealed and evacuated envelope, X-rays being generated at the anode as the result of impingement thereon of electrons emitted by the cathode element. The electron emitting element is commonly mounted in a cathode structure embodying a cup adapted to aid in directing, toward the anode, electrons emitted by the cathode element.

An important object of the invention is to provide improved means for mounting and insulating an emitter support stem in a cathode cup element of the character mentioned; a further object being to employ a block of suitable insulating material sized to fit snugly in a seat formed in the cup element, the block being formed with a support channel therein and sized to snugly receive an emitter support stem in accurately mounted position in the cup element.

Another important object is to employ a formed block of insulating material comprising magnesium oxide, lava, glass, porcelain, or the like, for mounting an emitter support stem in a cathode cup structure; a further important object being to provide improved means for mounting and retaining the block of insulation in mounted position on the cathode cup element, said means comprising a shell-like housing adapted to retain the block in operative position to support and insulate an emitter carrying stem mounted therein, even though said block may become cracked in service.

Another important object is to provide improved and simplified means whereby a filament support stem may be mounted and secured in precisely adjusted position in a stem supporting member, such as a cathode cup element.

The foregoing and numerous other important objects, advantages, and inherent functions of the invention will become apparent as the same is more fully understood from the following description, which, taken in connection with the accompanying drawings, discloses preferred embodiments of the invention.

Referring to the drawings:

Fig. 1 is a diagrammatic view of an electron flow device including a cathode structure embodying the present invention;

Fig. 2 is an elevation view, partially sectionalized, showing a structure embodying the invention;

Figs. 3 and 4 are sectional views taken substantially along the lines 3—3 and 4—4 in Fig. 2; and

Fig. 5 is an enlarged sectional view through a stem insulating and supporting device forming a part of the structure shown in Figs. 2 and 3.

To illustrate the invention the drawings show electron emission means comprising a cathode structure C of a sort well adapted for use in electron flow devices, such as an X-ray generating tube T. As shown, the tube comprises an anode A and the cathode structure C enclosed within and supported on a sealed and evacuated envelope E, which may be of any desired or preferred form and construction. X-ray generating devices operate as such in response to impingement on the anode of electrons emitted by the cathode, such electronic impingement resulting in the generation of X-rays at the anode, whence the rays may be transmitted through and outwardly of the enclosing envelope.

Metallic filaments are commonly employed as electron emitters in electron flow devices, such filaments being electrically excitable, for electron emission therefrom, as by the passage of electrical current there-through, from a power source located outwardly of the envelope of the device. Electrons emitted by an energized filament are commonly caused to travel toward and to impinge upon the anode of the device under the influence of an electron driving potential applied between the filament and the anode, as from a suitable source of electrical power also disposed outwardly of the envelope. In such electron flow devices, therefore, it is necessary to provide for mounting the electron emitting filament within the enclosing envelope and to provide for electrically connecting the filament not only with an external source of filament energizing power, 35 but also with a suitable external power source for applying electron driving potential between the anode and cathode of the device.

The present invention provides an improved mounting structure for supporting an electron emission filament in operative position within the sealed envelope of an electron flow device, structure also affording means for electrically connecting the supported filament with electrical power sources located outwardly of the envelope of the device in which the structure is or may be assembled for use.

As shown in the drawings, the electron emission means of the present invention comprises an electron emitting filament 11 and a support structure 12 for mounting the filament 11 within the sealed envelope of an electron flow device. The support structure 12 comprises a preferably cylindrical block 13 of any suitable material, such as steel, said block having an outwardly opening slot or groove 14 formed in its front end, the groove 14, in the illustrated embodiment, extending diametrically and transversely of the block 13 and opening at the opposite sides thereof, thereby facilitating the formation of the groove by a simple milling operation transversely across the front face of the block. The block 13 may also be formed with a pair of parallel, spaced apart, preferably cylindrical channels 15 and 15', said channels each opening at one end upon the bottom of the groove 14, the opposite ends of the channels opening into enlarged cavities 16 and 16' formed in and opening outwardly of the rear face of the block.

The filament 11 is supported with its axis lying substantially in the medial plane of the groove 14 and at a predetermined elevation between the bottom and open top of the groove, the opposite ends of the filament being mechanically and electrically connected on mounting stems 17 and 17', of suitable electrical conducting material such as molybdenum, supported on the block 13 in position extending coaxially with respect to the chan-

nels 15 and 15'. In that connection, the stems 17 and 17' may be formed with tapered end portions 18 and means, extending and secured in the seats 16 and 16', is provided for mounting the stems 17 and 17' in position on the block 13 presenting the tapered end portions 18 of the stems within the channels 15 and 15', the filament 11, at the opposite ends thereof, being formed with mounting extensions 19 adapted to be mechanically and electrically secured upon the tapered end portions 18 of the filament mounting stems.

In order to mount the filament supporting stems 17 and 17' accurately in position extending coaxially with respect to the channels 15 and 15', to thereby accurately locate the position of the supported filament 11 in the groove 14, the stems 17 and 17' may be received in preferably cylindrical mounting members 21 and 21' having portions adapted to extend snugly within the cavities 16 and 16', to thereby accurately locate the stems 17 and 17' with respect to the channels 15 and 15'. In the illustrated embodiment, the stem 17 is insulated from the block 13, while the stem 17' is electrically connected with the block so that the filament 11 may be energized for electron emission by electrically connecting the stem 17 and the block 13 with a suitable source of filament energizing power. It is, of course, within the contemplation of the present invention to electrically insulate both of the stems 17 and 17' from the block 13, in which case it would become necessary to provide means for connecting both of the stems with the filament energizing power source.

The mounting member 21 preferably comprises a cylindrical body of insulating material, such as magnesium oxide, lava, glass or porcelain, sized for snug interfitment at one end in the cavity 16. A retaining member comprising a cup-shaped shell 22, having an outstanding peripheral rim 23 and formed to snugly receive the portions of the insulating body 21 which extend outwardly of the cavity 16, is provided to support the member 21 in operative position on the block 13, the shell being secured on the block 13 in any preferred fashion and preferably by welding the rim 23 to the block. The insulating body 21 is formed with a channel 24 in coaxial alignment with the channel 15, and fitted with a preferably metal sleeve 25 having a peened portion 26 at one end of the sleeve, said sleeve being formed with a peripheral bead 27 medially thereof, whereby to secure the body 21 on the sleeve 25 between the peened portion 26 and the bead 27. The sleeve 25 has an end extending outwardly of the insulating body through an opening 28 formed in the bottom of the cup-shaped retaining member 22. The stem 17 and sleeve 25 are formed for snug sliding interfitment of the stem within the sleeve.

The cylindrical mounting member 21' may comprise a sleeve of electrical conducting material sized to snugly fit at one end within the cavity 16' and formed to snugly, yet slidingly receive the filament mounting stem 17', the member 21' being secured in any suitable or preferred fashion on the block 13.

The sleeves 21' and 25 preferably comprise metal which may readily be weldingly connected with the stems 17 and 17'. The sleeve 21' and the retaining shell 22 preferably comprise metal adapted to be readily connected, as by welding, with the block 13. To this end, the sleeves 21' and 25 and the retaining shell 22 may be made of nickel or a ferrous alloy of nickel, which is readily connectible by welding either with the steel block 13 or with the molybdenum filament mounting stems or both.

It will be seen from the foregoing that the emission element 11 and its support means, including the mounting stems 17 and 17', may be readily assembled on the block 13 with the element 11 located in precisely determined position in the groove 14 with minimum effort and substantially without requiring the parts to be handled. To this end, the block 13 may be placed face downwardly

in a suitable holding fixture for the reception of the stem mountings in the sockets 16 and 16'. The stem mounting, comprising the insulating body 21, the retaining shell 22, and the stem mounting sleeve 25, may then be secured in place, as by welding the rim 25 to the block 13; and the mounting, comprising the metal sleeve 21', may also be secured at one end in the socket 16'. The block 13 with attached stem mountings may then be inverted and secured in a suitable holder for the assembly of the stems 17 and 17' and the emission element 11.

If desired, the element 11 may be mounted on the stems 17 and 17' before the same are assembled in the stem mountings. To this end, the stems 17 and 17' may be clamped in desired spaced relation in a suitable holder 15 and the element 11 attached to the stem ends 18. Thereupon, the stems 17 and 17' may be applied in the stem mountings by employing the holder to aid in applying the ends of the stems 17 and 17', remote from the filament carrying ends thereof, through the channels 15 and 15' and into the ends of the sleeves 21' and 25. The stems may then be axially moved in the sleeves until the ends of the stems 17 and 17', which are remote from the filament carrying ends thereof, project outwardly of the sleeves 21' and 25, the stems 17 and 17' at such stage of the assembly being straight rods of sufficient length to allow the same to be held in the mountings with the stem ends 18 projecting outwardly of the upper face of the block 13.

The holder may then be removed from the stems 17 and 17' to permit the same to be drawn through the sleeves 21' and 25, as by gripping the ends of the stems 17 and 17' which project from the block remote ends of the sleeves 21' and 25, in order to draw the filament supporting stem ends 18 into the channels 15 and 15' to thereby support the filament in accurately determined position within the groove 14. Thereupon, the sleeves 21' and 25 may be welded upon the stem portions enclosed therein to secure the same against axial movement with respect to the block 13. After the welding operation, the stem 17' may be cut off opposite the block remote end of the mounting sleeve 21', while the stem 17 may be cut off at a desired distance outwardly of the mounting sleeve 25 and bent to form a connection lug 29, as shown in Fig. 1, for a purpose hereinafter more fully described.

Alternately, the stems 17 and 17', prior to the attachment of the emission element 11 thereon, may be applied in the stem mountings in position with their filament mounting ends 18 projecting above or outwardly of the front face of the block 13. The emission element 11 may then be mounted and attached to said ends of the stems, after which the stems may be drawn axially in the sleeves 21' and 25 to the position shown in Figs. 1 and 2, and weldingly secured in adjusted position in the sleeves in the manner mentioned supra.

In order to mount the electron emission structure on and in an enclosing envelope, such as the envelope of an X-ray tube, the same may be supported upon a pedestal or base 30 adapted to form a portion of the enclosing envelope. The pedestal 30, in turn, may carry a plurality of mounting stems 31 and 32 secured thereon in spaced apart relationship, the stem 32 at least being relatively insulated electrically from the remaining stems 31. As shown, the pedestal 30 may comprise a tubular glass member 130 having a closed end 33, forming a pinch seal in which the stems 31 and 32 are embedded, with the stem 32 and at least one of the stems 31 extending through and on opposite sides of the pinch seal. The stems 31 extend upwardly of the base 30 and have outwardly offset upstanding end portions 31' remote from the base in position to supportingly engage the block 13, while the stem 32 is provided with an offset lug 32' in position to register and engage with the connection lug 29 of the stem 17, when the block 13 is in position mounted on the stem portions 31'.
75

For the purpose of mounting the block 13 upon the stem portions 31', the block is provided with lateral grooves 34 which, for manufacturing convenience, may extend from one end of the block to its other end. These grooves are adapted to receive the stem portions 31' snugly therein; and a holding collar 35 may be applied snugly about the sides of the block 13 to hold the stem portions 31' in the grooves 34, and hence mount the block 13 upon the stems. To this end, the sleeve 35 is sized to tightly fit upon the block 13; and the same may be welded upon the block, especially at the stem portions 31', whereby to weldingly secure the stems in the grooves 34 and to secure the sleeve 35 on the stems and on the block 13. When the block 13 is thus mounted on the stem portions 31', the attachment lug 29 will be disposed in adjacent contact with the lug 32', and said lugs are preferably mechanically and electrically secured together, as by welding.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the forms herein disclosed being preferred embodiments for the purpose of illustrating the invention.

The invention is hereby claimed as follows:

1. An insulating structure for supporting the mounting stem of a cathode filament on a metal base formed with a duct therethrough, comprising a block of insulation formed with a channel opening at the opposite ends of the block, a cup-shaped retaining shell enclosing an end of said block and formed with outwardly extending portions for attachment on the base to hold the block in position with an end of its channel in alinement with the duct of the base, said shell having an opening formed in

the bottom thereof in position concentric with respect to the other end of said channel, and a sleeve extending in said channel and having an outwardly peened end in position for engagement with the duct facing end of the block 5 at the duct alined end of said channel, said sleeve being formed with a bead in position engaging the opposite end of the block to secure the sleeve against relative axial movement in said channel, the sleeve having projecting portions extending outwardly of the block beyond said bead and being sized to snugly yet slidingly receive the filament carrying stem, whereby the same may be mounted in accurately determined axially adjusted position in the sleeve.

2. An insulating structure as set forth in claim 1, wherein the sleeve comprises material readily connectible with a filament mounting stem disposed therein, whereby to secure such stem in axially adjusted position in the sleeve.

3. An insulating structure as set forth in claim 1, wherein the sleeve comprises metal adapted for integration with a metal filament mounting stem disposed therein to secure such stem in axially adjusted position in the sleeve.
